CLAIM

I claim the ornamental design for the two piece fastener device, as shown and described.

DESCRIPTION

FIG. 1 is a front elevational view of a two piece fastener device showing my new design.

FIG. 2 is a top plan view thereof;

FIG. 3 is a bottom plan view thereof;

FIG. 4 is a right side elevational view thereof;

FIG. 5 is a left side elevational view thereof; and,

FIG. 6 is a rear elevational view thereof.
